CLAIM

The ornamental design for a floor cleaner, as shown and described.

DESCRIPTION

FIG. 1 is a front perspective view of the floor cleaner;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the figures illustrate portions of the floor cleaner that form no part of the claimed design.

The dot-dash line is provided to illustrate a boundary of the claimed design.

Nilfisk-Advance, Inc.*, United States District Court for the District of Colorado, Case No. 1:13-cv-01284-CMA-MJW, filed Nov. 4, 2013, 232 pages.

Declaration of Wade Reitmeier in Support of Defendant Nilfisk-Advance, Inc.'s Response to Motion for Preliminary Injunction, (dated Aug. 16, 2013), *Kärcher North America, Inc., v. Nilfisk-Advance, Inc.*, United States District Court for the District of Colorado, Case No. 1:13-cv-01284-CMA-MJW, filed Aug. 16, 2013, 23 pages.

Defendant Nilfisk-Advance, Inc.'s Motion to Stay Litigation Pending Patent Reexaminations and Memorandum in Support, *Kärcher North America, Inc., v. Nilfisk-Advance, Inc.*, United States District Court for the District of Colorado, Case No. 1:13-cv-01284-CMA-MJW, filed Oct. 22, 2013, 15 pages.

Defendants Invalidity Contentions, *Kärcher North America, Inc., v. Nilfisk-Advance, Inc.*, United States District Court for the District of Colorado, Case No. 1:13-cv-01284-CMA-MJW, dated Dec. 2, 2013, 481 pages.

Defendants Reply Brief in Support of Its Motion to Stay Litigation Pending Patent Reexaminations, *Kärcher North America, Inc., v. Nilfisk-Advance, Inc.*, United States District Court for the District of Colorado, Case No. 1:13-cv-01284-CMA-MJW, filed Dec. 9, 2013, 11 pages.

Exhibit A of Notice of Defendant Nilfisk-Advance, Inc.'s Compliance With D.C.Colo.LPtR 8 and 9 and Invalidity Contentions, (dated Mar. 27, 2015), *Kärcher North America, Inc., v. Nilfisk-Advance, Inc.*, United States District Court for the District of Colorado, Case No. 1:13-cv-01284-CMA-MJW, 120 pages.

Exhibit B of Notice of Defendant Nilfisk-Advance, Inc.'s Compliance With D.C.Colo.LPtR 8 and 9 and Invalidity Contentions, (dated Mar. 27, 2015), *Kärcher North America, Inc., v. Nilfisk-Advance, Inc.*, United States District Court for the District of Colorado, Case No. 1:13-cv-01284-CMA-MJW, 73 pages.

Exhibit C of Notice of Defendant Nilfisk-Advance, Inc.'s Compliance With D.C.Colo.LPtR 8 and 9 and Invalidity Contentions, (dated Mar. 27, 2015), *Kärcher North America, Inc., v. Nilfisk-Advance, Inc.*, United States District Court for the District of Colorado, Case No. 1:13-cv-01284-CMA-MJW, 11 pages.

Fantomat Sale Sheet, Buzili-Werk Wagner GmbH & Co., date unknown.

First Amended Complaint With Jury Demand, *Kärcher North America, Inc., v. Nilfisk-Advance, Inc.*, United States District Court for the District of Colorado, Case No. 1:13-cv-01284-CMA-MJW, filed Sep. 25, 2013, 151 pages.
